UNITED STATES PATENT OFFICE.

FRANK G. WELSCH, OF SOUTH BEND, INDIANA, ASSIGNOR TO WESTINGHOUSE ELECTRIC AND MANUFACTURING COMPANY, A CORPORATION OF PENNSYLVANIA.

DESIGN FOR A HEAD FOR LIGHTING UNITS.

Application filed June 23, 1928. Serial No. 27,243. Term of patent 14 years.

To all whom it may concern:

Be it known that I, FRANK G. WELSCH, a citizen of the United States, residing at South Bend, in the county of St. Joseph and State of Indiana, have invented a new, original, and ornamental Design for a Head for Lighting Units, of which the following is a specification, reference being had to the accompanying drawings, constituting a part hereof.

Figure 1 is a side elevational view of a

head for a lighting unit showing my new design; and

Fig. 2 is an end elevational view of the head for lighting unit shown in Fig. 1.

I claim:—

The ornamental design for a head for lighting units substantially as shown.

In testimony whereof, I have hereunto subscribed my name, this 12th day of June, 1928.

FRANK G. WELSCH.
